UNITED STATES PATENT OFFICE.

JOHN T. BREECE, OF PORTSMOUTH, OHIO, ASSIGNOR OF ONE-HALF TO CHARLES C. BREECE, OF PORTSMOUTH, OHIO.

METHOD OF BENDING WOOD.

1,052,405.

Specification of Letters Patent.

Patented Feb. 4, 1913.

Application filed September 25, 1911. Serial No. 651,100.

To all whom it may concern:

Be it known that I, JOHN T. BREECE, a citizen of the United States, residing at Portsmouth, in county of Scioto and State 5 of Ohio, have invented certain new and useful Improvements in Methods of Bending Wood, of which the following is a specification.

My invention relates to an improved 10 method of bending wood, and is an improvement upon the invention set forth in Letters Patent No. 938,366, granted to me October 26, 1909, in which the preferred procedure was to form two rims at one bend of material, one of which was a solid rim, and the other a so-called "built-up" rim. At the time the foregoing patent was applied for, a solid rim seemed to be a necessary element in carrying out my process, but in the light 15 of subsequent experiments and discoveries it has been found that in lieu of the solid rim a built-up rim may be used with equal, if not still more satisfactory, results, of material more nearly of uniform thickness and 20 by dispensing with the solid rim and using thinner material but not what is termed veneer, it is possible to entirely dispense with the necessity of steaming which is required in order to make the solid rim flexible. In my present invention in lieu thereof, 25 three or more built-up rims composed of layers properly proportioned as to thickness are bent and fashioned at a single operation, without the use of any solid rim. This invention, like the other, is especially adapted 30 for bending table rims, although its application may be extended indefinitely, and this invention consists in certain novel procedure, which will be hereinafter described 35 and pointed out in the claim.

In the accompanying drawings:—Figure 1 is a diagrammatic view in side elevation illustrating a machine in which the bending is accomplished, just prior to the bending, 40 Fig. 2 is a similar view showing the parts bent around the form, and Fig. 3 is an enlarged transverse sectional view through three sets of built-up rims.

In this invention each rim is preferably 45 composed of three properly portioned layers or veneers 1, 2, and 3, respectively. These strips are coated on their inner surfaces with glue, preferably by passing them through a machine for this purpose, although it

might be done by hand. Then the rim thus 55 built up of three layers or veneers is placed on the flexible bending band 5 of the machine. This band may be made sufficiently wide to accommodate one or more rims, as the case may be. Then over this or these 60 rims, I place an interposed layer 6 of flexible material impervious to water, such as sheet or galvanized iron, for instance. On top of this layer of flexible material a corresponding number of built-up rims of three layers 65 is superimposed, then another, also of flexible material impervious to water is placed on top, and over that a third rim or set of rims built up of three layers or veneers is placed. Then they are placed in the machine, as 70 illustrated in Fig. 1, and bent cold as shown in Fig. 2, the pressure upon the ends of the veneers through blocks 10, 10, on levers 11, 11, during the bending having the effect of creating a uniform outward pressure of the 75 inner built-up rims throughout their entire length, thus causing the entire contacting surfaces of veneers or layers to come into solid contact with one another, causing them to adhere throughout their entire contact- 80 ing surfaces, and produce the effect of a perfectly solid rim. In other words, the end pressure results in an equalized and evenly distributed radial pressure throughout the entire length of the inside rims, so that 85 every point of contact is subjected to equal compression, and the built-up layers are brought tight together and made to permanently adhere at every point of contact throughout their entire area. 90

Having fully described my invention, what I claim as new and desire to secure by Letters Patent, is:—

The herein described method or process of bending wood, which consists in superimposing a plurality of unsteamed built-up rims only upon a flexible bending member, the layers of each built-up rim properly proportioned as to thickness and having adhesive material applied to adjacent surfaces, 95 interposing layers of flexible material between said sets of built-up rims, then bending said superimposed built-up rims with intermediate flexible layers around a form and simultaneously applying endwise pressure to the innermost layers against the remaining layers confined by the flexible bending member whereby the several superim- 100 105

posed built-up rims are simultaneously subjected to uniform pressure throughout their length and area due to the bending and the endwise pressure exerted upon the innermost 5 layer or layers against the lateral and confining pressure of the flexible bending member.

In testimony whereof I affix my signature, in the presence of two witnesses.

JOHN T. BREECE.
